UNITED STATES PATENT OFFICE.

NELS CHRISTIAN NELSEN, OF OAKLAND, CALIFORNIA, ASSIGNOR OF ONE-THIRD TO LEWIS N. WOOD, OF OAKLAND, AND TWO-THIRDS TO STERLING W. SMITH, OF BERKELEY, CALIFORNIA.

WALL-BED.

1,243,336.

Specification of Letters Patent.

Patented Oct. 16, 1917.

Application filed May 16, 1914. Serial No. 839,067.

To all whom it may concern:

Be it known that I, NELS CHRISTIAN NELSEN, a citizen of the United States, residing at Oakland, in the county of Alameda and 5 State of California, have invented certain new and useful Improvements in Wall-Beds, of which the following is a specification.

This invention relates to improvements in folding wall beds of the type wherein a 10 panel of the wall is pivotally mounted in a vertical plane and has the bed attached to one side thereof, the opposite side having any ornamental or useful object attached or placed thereon.

15 The principal object of my invention is to provide means whereby this panel of the wall may be mounted so as to be easily turned to its opposite position.

Another object of my invention is to provide 20 improved mechanism for supporting the bed to the movable wall section so that the bed may be easily raised and lowered, and in general to improve, simplify, and provide a more convenient structure for 25 wall beds than heretofore used.

With these and other objects in view my 30 invention consists in the novel construction and arrangement of parts as herein described and more specifically pointed out in the appended claims.

For a full comprehension of my invention reference should be had to the accompanying drawing forming a part of this 35 specification wherein,

Figure 1 is a view in plan of the improved bed showing the same set in a recess in the wall and the bed positioned within the wall.

Fig. 2 is a view in section along the line 2-2, Fig. 1, showing the bed in its folded 40 position within the recess and also showing the same in dotted outlines as positioned for use.

Fig. 3 is a view in plan of a roller device on which the bed is pivotally mounted.

45 Fig. 4 is a view in side elevation of the latter device.

Fig. 5 is a view in end elevation of a roller device used on the end of the wall panel.

50 Fig. 6 is a view in side elevation of the same.

Referring to the corresponding parts in the several views by the same numerals of reference, 1 denotes a wall in which a recess 2 is provided for the reception of my improved bed. Mounted in the opening of

this recess is a paneled wall section 3, which entirely closes this opening. The upper and lower edges of this wall section are provided with grooved channel members 4 and central of the opening in the floor and the ceiling of the recess is mounted the device 5 shown in Figs. 3 and 4. Each of these devices consists of a flat plate 6 having attached centrally thereof the pivot pin 7. A plate 8 is fastened to the floor or ceiling 60 and has therein an opening threaded for the socket member 9. The latter is in threaded engagement with the plate 8 and a lock nut 10 is provided to hold the same in any adjusted position. The socket member is provided with a bore 11 for the reception of the pivot pin 7, the plate 6 being 65 thus pivotally mounted in the socket 9 and vertically adjustable in the plate 8.

Adjacent the ends of plate 6 are provided 70 openings 12 in which are revolvably mounted rollers 13, the same extending outside the surface of the plate on the side opposite the pivot pin. In like manner are provided transverse openings 14 and mounted therein 75 on each side of the plate are rollers 15, which extend outside of the slot on the sides of the plate. The movable wall section 3 is mounted on this device 5, the rollers 12 contacting 80 with the web of the channel member and the roller 15 contacting with the flanges 85 thereof.

On one end of the wall section as at 16 is mounted the caster like device 17 shown in Figs. 5 and 6. This device consists of a 90 T-shaped frame 17' in the arms of which are provided slots 18 on which are revolvably mounted the rollers 18' and in the extension of the stem is held a pin 19 on the ends of which are revolvably mounted rollers 20'. 95 The stem 20 of member 17 is cylindrical in shape and is pivotally mounted in a thimble 21, which is seated in the under surface of the wall section 3.

While I have shown this device as being 100 only mounted in the lower edge of the wall section, I may find it advantageous to mount one in the upper edge also. This device works in a slotted curved track member 22. The slot of this track is of T-shape 105 and the rollers 20 at various times in the movement of the wall section contact with the bottom of the groove therein and at other times with the underside of the inwardly extending flange 23, while the rollers 110

18 contact with the edges of these inwardly extending flanges.

The bed mounted on the one side of this wall section consists of the longitudinal members 24 having the ornamental foot frame 25 and folding legs 26. The head frame 27 is pivotally mounted at 29 on an extension 28 from the longitudinal members. 30 denotes an angle bar attached to the surface of the wall section and riveted thereto is a laterally extending member 31, in the outer end of which is a curved slot 32. A headed pin 33 extends through this slot and engages the side members 24. Riveted to 24 adjacent the end thereof is a plate 34 to which is pivotally mounted a link 35, the other end of which is pivotally attached to the angle 30 as shown at 36, and 37 denotes a coiled spring which is attached to the link intermediate its ends and to a bar 38, which extends at right angles from angle iron 30 and is rigidly braced thereto.

The head member is provided on the back with an eye 40 through which passes a rod 41, this rod being pivotally mounted on its upper end to an arm 42, which in turn is pivotally attached to the wall section 3.

The operation of my improved bed is as follows:—By turning the latch 45 and pulling on the knob thereof this end of the bed is pulled outwardly, the opposite end being guided in the track 22 by means of the caster 17. The first part of this track is curved on a radius struck from the center of the pivot 35 of the roller device 5, thus the first movement of the wall section is to bring one end out of the recess without binding against the sides thereof. On further movement of the wall section the caster in the track 22 causes the wall section to be pushed outwardly, the channels 4 sliding on the rollers of the device 5.

During this movement the greater weight of the wall section is outside of the recess, consequently, the rollers 20 of the caster 17 will contact with the inside of flanges 23 thus holding the weight of the wall and attached parts to prevent binding thereof. The wall section is completely turned around until the caster 17 rests in the opposite end of the track placing the bed on the outside of the wall.

By grasping the upper portion of rod 24 this end may be pulled outwardly causing the pivot 33 to move upwardly in the slot 32 by reason of the push exerted thereon by the link 35. As soon as the upper end of the bed is moved outwardly a short distance the weight begins to act and pull the same down, which causes the spring 37 to be brought into tension thus preventing the bed from moving down with a jar and at the same time storing up energy which is useful in returning the bed to its raised position. As the bed is lowered the head frame is auto-

matically raised due to the upper edge being guided on rod 41 until when the side bars 24 or horizontal head member will be in a vertical position and other parts will be positioned as shown in dotted outlines 70 in Fig. 2. In folding the bed the spring 37 counterbalances the weight of the foot portion so that the bed is easily folded to its upright position.

It will thus be apparent that I have provided a device which effectively accomplishes the objects set forth in the beginning of this specification.

While I have shown this preferred embodiment of my invention it will be understood that various changes in form and minor details of construction may be resorted to without departing from the scope of the claims.

What I claim as new and wish to cover by Letters Patent is:—

1. The combination with a wall recess, of a turnable wall panel for closing the opening therein and carrying an article of furniture on one side, a grooved track along the upper and lower edges of said panel, pivotally mounted guide members on the wall slidably received in said tracks and forming journals about which said panel turns and on which said grooved tracks are adapted to roll, a caster pivotally mounted adjacent to one side of said panel, and a grooved track adapted to receive said caster, whereby when the panel is swung to reverse its position it will be shifted edgewise along the guide members.

2. The combination with a wall recess, of a wall panel turnable about a vertical axis for closing the opening in said recess and carrying an article of furniture on one side, a longitudinal, grooved track along the upper and lower edges of said panel, guide members pivotally mounted on the wall centrally of the opening, and slidably received in said tracks and forming journals about which said panel turns, rollers pivotally mounted in the faces of said guide members and adapted to contact with the sides and bottom of said grooved track, a grooved, substantially semi-elliptical track in the rear of said panel and extending from under one corner to the opposite corner thereof, a caster pivotally mounted adjacent to one side of said panel and adapted to roll in said elliptical grooved track, whereby when the panel is swung to reverse its position it will be shifted edgewise along the guide members.

3. The combination with a wall recess, of a turnable wall panel for closing the opening therein and carrying an article of furniture on one side, a grooved, longitudinal track along the upper and lower edges of said panel, a guide member on which said track is adapted to roll, said guide members

- being pivotally mounted on the wall centrally of the opening and forming the journals about which said panel turns, a grooved, substantially semi-elliptical track mounted 5 in the rear of said panel and having the ends extending under the opposite sides of said panel, a caster pivotally mounted in one side of said panel and having horizontal rollers adapted to contact with the sides of the 10 groove of said elliptical track, and vertical rollers adapted to contact with the bottom of said groove and with the underside of inwardly extending flanges on the upper edges thereof, whereby when the panel is swung 15 to reverse its position it will be shifted edgewise along the guide members.
4. The combination with a wall recess, of a turnable wall panel for closing the opening therein and carrying an article of furniture on one side, a track along the upper and lower edges of said panel, guide members on the wall disposed in the opening, in which said panel turns and on which said tracks are adapted to roll, a bearing member 20 mounted adjacent to one side of said panel, and a track adapted to receive said bearing member, whereby when the panel is swung to reverse its position it is shifted edgewise along the guide members.
- 25 5. The combination with a shallow closet, of a panel wider than twice the depth of the closet turnably mounted in an opening therein for closing the same and adapted to carry on one side an article of furniture, 30 guide members on the closet slidably engaging the upper and lower edges of the panel and about which the panel turns when swung, and a curved guide with which the panel 35 engages to cause it to be shifted endwise when being swung about the guide members on the closet, whereby the panel 40 may reverse its position within the opening to present the article of furniture thereon either within or without the closet.

may reverse its position within the opening to present the article of furniture thereon either within or without the closet.

6. The combination with a shallow closet, 45 of a panel wider than twice the depth of the closet turnably mounted in an opening therein for closing the same and adapted to carry on one side an article of furniture, 50 guide members on the closet slidably engaging the upper and lower edges of the panel and about which the panel turns when swung, an elliptical track within the closet, and a member on the panel to engage with said track to cause said panel to be shifted 55 endwise when being swung about the guide members on the closet, whereby the panel may reverse its position within the opening to present the article of furniture thereon either within or without the closet.

60 7. The combination with a shallow closet, of a panel wider than twice the depth of the closet turnably mounted in an opening therein for closing the same and adapted to carry on one side an article of furniture, 65 flanged tracks on the upper and lower edges of said panel, pivoted guide members on the closet slidably engaging with said tracks and about which the panel turns when swung, and a curved guide with which the panel 70 engages to cause it to be shifted endwise when being swung about the guide members on the closet, whereby the panel may reverse its position within the opening to present the article of furniture thereon either within 75 or without the closet.

In testimony whereof I affix my signature in presence of two witnesses.
